UNITED STATES PATENT OFFICE.

CHARLES A. CRARY, OF HUNTINGTON, WEST VIRGINIA, ASSIGNOR TO
ENTERPRISE SOAP WORKS, OF NASHVILLE, TENNESSEE, A CORPO-
RATION OF TENNESSEE.

DESIGN FOR SOAP.

SPECIFICATION forming part of Design No. 36,078, dated September 16, 1902.

Application filed May 3, 1902. Serial No. 105,855. Term of patent 14 years.

To all whom it may concern:

Be it known that I, CHARLES A. CRARY, a citizen of the United States, residing at Huntington, in the county of Cabell and State of West Virginia, have invented and produced a new, original, and ornamental Design for Soap; and I do hereby declare the following to be a full, clear, and exact description of the same, reference being had to the accompanying drawings, forming a part thereof.

In the accompanying drawings, Figure 1 is a perspective view of a cake of soap embodying the features of my design. Fig. 2 represents a view in side elevation of the same. Fig. 3 is a top plan view of the same, embodying my design.

The essential feature of my design is a rectangular cake having continuous oval faces rising from the rectangular portion, the ends of the cake being beveled in opposite directions and the surface between the oval faces and the beveled ends being flat and giving to the cake the appearance of having a broad flat band around it or the appearance of a rectangular body portion having raised oval portions extending therefrom and beveled ends.

1 in the drawings refers to a rectangular cake formed with continuous oval faces 2, having the ends beveled, as at 3 3, in opposite directions, the surface between the oval faces and the beveled ends being flat, so that the cake has to the eye the appearance of having a rectangular body portion, oval faces, and beveled ends, the rectangular portion giving to the cake the appearance of a flat band all around the same.

In Figs. 1 and 3 I have shown my new design for a cake of soap having upon it the representation of a fancy panel.

Having now described my invention, what I claim is—

The ornamental design for a cake of soap, substantially as herein shown and described.

In testimony whereof I hereunto affix my signature in presence of two witnesses.

CHAS. A. CRARY.
